Primary Examiner — Robert M Spear*Assistant Examiner* — Marissa J Cash(74) *Attorney, Agent, or Firm* — MeadWestvaco Intellectual Property Group(57) **CLAIM**

The ornamental design for an industrial trigger sprayer shroud, as shown and described.

DESCRIPTION

FIG. 1 is a perspective view of an industrial trigger sprayer shroud showing the new design;

FIG. 2 is a back perspective view of the new design;

FIG. 3 is a left view of the new design;

FIG. 4 is a right view of the new design;

FIG. 5 is a front view of the new design;

FIG. 6 is a back view of the new design; and,

FIG. 7 is a top view of the new design.

The broken-lines in the drawings represent unclaimed environmental subject matter and form no part of the claim.
